HYDRODYNAMIC FLUID COUPLING

Fritz Kugel, Heidenheim-on-the-Brenz, Germany

Application August 10, 1936, Serial No. 95,301
In Germany August 14, 1935

14 Claims. (Cl. 60—54)

The invention relates to hydraulic power transmitting devices, such as hydraulic couplings or torque converters, and in particular to the provision, in such devices, of a rotating reservoir chamber connected by separate passages to the working chamber so as to take up the working fluid temporarily not required, and thereby to effect a quick emptying and filling of the fluid circuit.

- 10 Hitherto, in such devices, the discharge of the working fluid to the reservoir chamber has frequently been effected by scoop tubes which started to work as soon as a sufficiently large difference in speed existed between the fluid and the scoops. 15 In such prior devices the fluid returned to the reservoir chamber from the working chamber through the same canals by which it entered, as soon as the slip decreased in response to a change in the operating conditions. By this use of a common intake and discharge passage, either the filling or the emptying conditions were interfered with and unfavorably influenced.

One object of the present invention is to provide a hydraulic power transmitting device wherein 25 two separate connections between the reservoir chamber and the working chamber allow the working fluid to enter and leave the working chamber by separate paths, thus providing the most favorable arrangement for filling and emptying the working chamber.

Another object is to provide such a device wherein the reservoir chamber is arranged in the primary or driving part of the device by reason of the fact that the latter rotates always at maximum speed so that the working fluid stored there stands under high pressure, due to centrifugal force. If the speed of the prime mover operating the primary or driving part of the hydraulic coupling or torque converter can be varied, centrifugal force may be utilized to effect the entrance of the working fluid from the rotating reservoir chamber into the working chamber through passages in the primary wheel, these being preferably adjustable. The centrifugal force 35 may be varied by changing the speed and thus the slip between the wheels. If the speed of the prime mover is not variable, a valve is arranged to control the supply of fluid to and from the working chamber and rotating chamber, respectively. This valve, operated automatically or manually, controls the supply of working fluid from the reservoir chamber to the working chamber.

Another object is to provide such a device with 50 scoops at the circumference of the secondary part,

these scoops being arranged to effect a complete emptying of the working chamber. In order to obtain the large slip between primary and secondary parts necessary for the working of the scoops, the speed of the primary wheel is either 5 decreased or the discharge valve of the reservoir chamber is connected to a ring valve which may throttle or even interrupt the flow of fluid to the working chamber.

In the drawings:

Figure 1 is a vertical longitudinal section through a fluid coupling with a control valve in its closed position.

Figure 2 is a similar section through a fluid coupling with the control valve in its open position.

Figure 3 is a similar section through a fluid coupling having an automatic regulating device for the control valve.

Figure 4 is a cross section along the line 4—4 in Figure 1, showing the scoop tube construction.

Referring to the drawings in detail, in Figure 1 the primary wheel *a* is connected with a variable speed engine by the driving shaft *a*¹. The secondary wheel *b* is mounted on the driven shaft *b*¹. A wall *a*² connected with the primary wheel *a*, together with the back of the latter, forms the rotating chamber *u*, while coupling casing *a*³ extends over the secondary part or turbine wheel *b* and forms a bearing for shaft *b*¹ and is sealed against the shaft *b*¹ by the stuffing box *f*. Primary wheel *a* is provided with passages *p* the openings of which are preferably adjustable. These passages *p* form a connection between the chamber *u* and the core space *r*. In the secondary part *b*, scoops *m* and canals *n* are provided to return the working fluid from the transmission circuit to the chamber *u* along overflow edge *t*.

When starting the coupling, the secondary part *b* of the coupling is at rest. As the speed of the primary part *a* increases, the fluid in the chamber *u* is urged from the chamber *u*, through the passages *p* by centrifugal force, thus filling the fluid circuit, i. e. engaging the coupling. With decreasing speed of the engine, and thus of the primary part *a*, the scoops *m* gradually come into operation, due to the increased slip, and empty the fluid circuit to the chamber *u*.

In Figures 1 and 2 the blade wheel, driven by a constant speed engine, is marked *a*. This wheel is connected with the engine shaft *a*¹ by means of a shell *a*², which is integral with the engine shaft *a*¹. Blade wheel *b* is fastened on the shaft *b*¹ of the machine, to be driven and inclosed by the coupling casing *a*³ connected to the primary blade 55

wheel *a*. The coupling casing *a*³ forms a bearing for the output shaft *b*⁴ and is sealed thereagainst by means of the stuffing box *j*. The back of the primary blade wheel *a* and the shell *a*² connected thereto, inclose the hollow space *u* serving as a reservoir chamber for the working fluid which is temporarily not required by the coupling. A number of passages *p* lead from this chamber to the core space *r* of the coupling. These passages *p* can be closed by the valve body *s*, to which the ring valve *s*¹ is connected. In the position indicated, the valve *s*¹ closes the blade canals of the primary wheel and at the same time the annular portion *s*³ also closes the passages *p* leading to the core space *r*. The valve body *s* can be adjustably moved from the outside, adjusting sleeve *i* in an axial direction through the operating connection formed by the pin *j* and the slot *k*. By moving the valve body *s* towards the driving shaft *a*¹, the circuit is thereby opened for working fluid through the blade canals of the primary wheel *a* from the reservoir chamber *u* by way of the core space *r* and passages *p*. Secondary blade wheel *b* is fitted with scoops *m* connected by canals *n* to the part of chamber *u* near the axis.

When starting with the valve *s*¹ closed (Figure 1), the secondary part or rotor *b* is at rest. With increasing speed of the primary part or rotor *a*, however, any fluid that might have remained between the blade wheels will be thrown out by centrifugal force, caught by the scoops *m* and led through the canals *n* to the space *q* near the axis, whence it then flows back to the chamber *u*. Since a return of the fluid accumulated in the chamber *u* into the working circuit is made impossible by the closed condition of the valve *s*¹, an almost complete discharge of the working fluid from the coupling spaces *a*, *b*, *q* and *r* to the chamber *u* is secured. This means that the coupling cannot transmit any torque when started with the valve *s*¹ in this condition.

The working fluid accumulated in the chamber *u* is now influenced by the rotating walls and subjected to centrifugal pressure. As soon as the valve body *s* is moved to the left by means of displaceable sleeve *i* (Figure 2), the consequent shifting of the ring valve *s*¹ uncovers the passages *p* so that the fluid passes through the passages *p* into the working space of the coupling at high velocity. The coupling thereby acquires the capacity to transmit torque, i. e. the coupling is engaged. Secondary runner *b* then starts to rotate, whereupon the fluid which is still discharged by scoops *m* to the rotating axis does not reach the chamber *u* any more, but is immediately returned to the coupling spaces *a*, *b* and *r* by centrifugal force. The scooping effect of the scoops *m* decreases with the increasing speed of the secondary wheel *b* and finally ceases completely, due to the centrifugal force counteracting the passage of the fluid through the canals *n*. The coupling spaces *a*, *b* and *r* thus remain completely filled, whereby the full transmitting capacity of the coupling is obtained.

When stopping the coupling, the valve body *s* is moved to the right (Figure 1), whereupon the ring valve *s*¹ closes the openings to the blade canals of the wheels *a* and *b*, and simultaneously closes the passages *p*. This interruption of the fluid circuit immediately causes a considerable reduction in the transmission capacity of the coupling so that the speed of the secondary wheel *b* decreases considerably, due to the load on the machine being driven. This speed reduction causes the scoops *m* to become operative again to

return the fluid to the chamber *u* so that finally a complete emptying and disengagement of the coupling is again obtained, and the driven machine comes to rest.

In order to assist the flow of the fluid from the secondary wheel *b* to the chamber *u*, it is preferred to provide the secondary wheel *b* with an overflow edge *t* projecting into the chamber *u*. It is further preferred to construct the valve body *s* in such a manner that it will also form one of the lateral limiting walls of the chamber *u*. Accordingly, when the valve body *s* is moved, for the purpose of filling and thus engaging the coupling, this wall will have a displacing effect on the fluid in the chamber *u*, whereby the filling of the coupling is accelerated.

Thus it will be seen that in the operation of the coupling shown in Figures 1 and 2 the fluid contained in the space *u* is urged outwardly by reason of the centrifugal force created by the rotation of the coupling. This fluid is forced through the bores *p* in the coupling rotor *a* by reason of this centrifugal force, when the valve member *s* and its annular portion *s*³ are shifted to the left, as shown in Figure 2. Thus the ring slide valve *s*¹ and the annular portion *s*³ cooperate to produce the desired result. The ring slide valve *s*¹, by altering the circulation within the coupling rotors *a* and *b*, increases the slip in the rotor *a* so that the scoop tube comes into operation, whereupon the fluid within the rotors *a* and *b* is conducted through the scoop tubes *m* and the space *q* into the chamber *u*. To prevent the escape of the fluid at the same time through the bores *p*, the annular portion *s*³ comes into action, and closes the inlets to the bores *p*. When it is desired to fill the coupling again, the slip is once more reduced by moving the slide valve *s*¹ and annular portion *s*³ by shifting the shift member *i* so that the working fluid can flow freely through the bores *p*, from the chamber *u*, to the rotors *a* and *b* of the coupling.

In the modified construction of Figure 3 there is shown means to provide for an automatic engaging and disengaging of the coupling in response to the input and output speeds or to the slip. This is realized by utilizing a centrifugal mechanism *c*, which becomes operative to displace the valve body *s* as soon as a certain speed is exceeded.

This centrifugal mechanism *c* consists of a fly weight *c*¹, on an arm *c*², pivotally mounted on the pivot member *c*³. Likewise mounted upon the pivot member *c*³ is an arm *c*⁴, pivotally connected at its opposite end to a link *c*⁵. The link *c*⁵ is pivotally attached to a lug *s*² mounted upon the valve body *s*.

In the operation of the apparatus shown in Figure 3, the rotation of the casing *a*² creates centrifugal force which causes the fly weight *c*¹ to move outward, swinging the arm *c*² to move the link *c*⁵ to the left. This action shifts the valve body *s* to the left, overcoming the thrust of the coil spring *h*¹ and causes the ring valve *s*¹ to open the passages *p*.

It will be understood that I desire to comprehend within this invention such modifications as come within the scope of the claims and the invention.

I claim:

1. In a hydraulic power transmitting device, a working chamber, a driving rotor and a driven rotor therein, and inclosing casing for said device additionally forming the outer wall of a rotatable reservoir connected to one of said rotors

and extending substantially to the periphery thereof, a fluid passage extending from the peripheral region of said reservoir and running in an axial direction to said working chamber, and 5 a peripherally disposed valve member arranged adjacent said fluid passage and movable relatively thereto for varying the flow of fluid therethrough.

2. In a hydraulic power transmitting device, 10 a working chamber, a driving rotor and a driven rotor therein, a rotatable reservoir associated in one of said rotors, a fluid passage interconnecting said reservoir and said working chamber, a valve member arranged adjacent said fluid passage and movable relatively thereto for varying the flow of fluid therethrough, and means responsive to the rotation of one of said rotors for automatically varying the setting of said valve member.

20 3. In a hydraulic power transmitting device, a working chamber, a driving rotor and a driven rotor therein, a rotatable reservoir associated in one of said rotors, a fluid passage interconnecting said reservoir and said working chamber, and 25 a valve member having portions movable relatively to said fluid passage and also relatively to the fluid circuit within said working chamber for varying the flow of fluid through both said fluid passage and said working chamber fluid circuit.

30 4. In a hydraulic power transmitting device, a working chamber, a driving rotor and a driven rotor therein, a rotatable reservoir associated in one of said rotors, a fluid passage interconnecting said reservoir and said working chamber, a 35 valve member arranged adjacent said fluid passage and movable relatively thereto for varying the flow of fluid therethrough, means responsive to the rotation of one of said rotors for automatically varying the setting of said valve member, and yielding means urging said valve member toward its closed position.

5. In a hydraulic power transmitting device, a working chamber, a driving rotor and a driven rotor therein, a rotatable reservoir associated in 45 one of said rotors, a fluid passage interconnecting said reservoir and said working chamber, a valve member having portions movable relatively to said fluid passage and also relatively to the fluid circuit within said working chamber for 50 varying the flow of fluid through both said fluid passage and said working chamber fluid circuit, and yielding means urging said valve member toward its closed position.

6. In a hydraulic power transmitting device, 55 a working chamber, a driving rotor and a driven rotor therein, an inclosing casing for said device additionally forming the outer wall of a rotatable reservoir connected to one of said rotors and extending substantially to the periphery thereof, a relatively short fluid intake passage 60 extending from said reservoir at a location near the periphery of one of said rotors to said working chamber, a separate discharge passage extending from said working chamber to said reservoir, and a peripherally disposed valve member 65 arranged adjacent said intake passage and movable relatively thereto for varying the flow of fluid therethrough.

7. In a hydraulic power transmitting device, 70 a working chamber, a driving rotor and a driven rotor forming a working circuit therein, a fluid reservoir, a fluid passage interconnecting said fluid reservoir and said working chamber, and a valve member having portions movable relatively 75 to both said fluid passage and working circuit

for varying the flow of fluid through both the said fluid passage and said working circuit.

8. In a hydraulic power transmitting device, a working chamber, a driving rotor and a driven rotor forming a working circuit therein, a fluid 5 reservoir, a fluid passage interconnecting said fluid reservoir and said working chamber, and a valve member having portions movable relatively to both said fluid passage and working circuit for varying the flow of fluid through both the said fluid passage and said working circuit, said valve portions being movable simultaneously across said fluid passage and said working circuit, whereby to valve the fluid flow therethrough by a single motion of said valve. 15

9. In a hydraulic power transmitting device, a working chamber, a driving rotor and a driven rotor forming a working circuit therein, a fluid reservoir, a fluid passage interconnecting said fluid reservoir and said working chamber, a valve 20 member having portions movable relatively to both said fluid passage and working circuit for varying the flow of fluid through both the said fluid passage and said working circuit, and means responsive to the rotation of one of said rotors 25 for automatically varying the setting of said valve member.

10. In a hydraulic power transmitting device, a working chamber, a driving rotor and a driven rotor forming a working circuit therein, a fluid 30 reservoir, a fluid passage interconnecting said fluid reservoir and said working chamber, a valve member having portions movable relatively to both said fluid passage and working circuit for varying the flow of fluid through both the said 35 fluid passage and said working circuit, and yielding means urging said valve member toward its closed position.

11. In a hydraulic power transmitting device, a working chamber, a driving rotor and a driven 40 rotor therein, an inclosing casing for said device additionally forming the outer wall of a rotatable reservoir connected to one of said rotors and extending substantially to the periphery thereof, a fluid intake passage extending from the periphery of said reservoir to said working chamber, a separate fluid discharge passage interconnecting said reservoir and said working chamber, and peripherally disposed valve means for controlling the flow of fluid through one of said 45 passages. 50

12. In a hydraulic power transmitting device, a working chamber, a driving rotor and a driven rotor therein, an inclosing casing for said device additionally forming the outer wall of a rotatable 55 reservoir connected to one of said rotors and extending substantially to the periphery thereof, a fluid intake passage extending from the periphery of said reservoir to said working chamber, a separate fluid discharge passage interconnecting said reservoir and said working chamber, and peripherally disposed valve means having a valve member disposed near the periphery of one of said rotors for controlling the flow of fluid through said intake passage. 60

13. In a hydraulic power transmitting device, a working chamber, a driving rotor and a driven rotor therein, a rotatable reservoir associated with one of said rotors, a fluid intake passage and a fluid discharge passage interconnecting 70 said reservoir and said working chamber, valve means for controlling the flow of fluid through one of said passages, and means responsive to the rotation of one of said rotors for automatically varying the setting of said valve means. 75

14. In a hydraulic power transmitting device, a working chamber, a driving rotor and a driven rotor therein, an inclosing casing for said device additionally forming the outer wall of a rotatable reservoir connected to one of said rotors and extending substantially to the periphery thereof, a relatively short fluid intake passage extending from the periphery of said reservoir to said working chamber, a separate fluid discharge passage interconnecting said reservoir and said working chamber, valve means having a valve member dis-
- posed near the periphery of one of said rotors adjacent said working chamber for controlling the flow of fluid through said intake passage, and a scoop on said discharge passage within said working chamber arranged to assist the emptying of the working fluid from said working chamber into said reservoir in response to the attainment of a predetermined slip between said driving and driven rotors.

FRITZ KUGEL. 10
